ATTORNEYS.

UNITED STATES PATENT OFFICE.

WILLIAM C. KOCH, OF ST. PAUL, MINNESOTA.

DISPLAY CASE FOR BRICK.

Application filed April 20, 1925. Serial No. 24,317.

It is my object to provide a novel tray hereinafter described. To maintain the or case adapted to hold a number of brick strips 9, 9^a and 9^b in proper, upright and spaced relation, I provide a series of short, transverse bars 11, preferably provided with thin sheet metal bases 12 adapted to rest 55 upon the bottom 8 of the tray. When in place in the display case, the strips 9, 9^a and 9^b and bars 11 illustrate the mortar in which the bricks are to be laid.

A further object is to provide a display case of this kind with efficient and simple means for firmly holding the brick samples, said means being adapted to be quickly and 10 easily manipulated to grip or release the samples. Such means facilitate change in the character of the bricks displayed and in their arrangement or the design of the wall illustrated.

Another object of this invention is to provide gripping members formed to so direct lateral pressure as to oppose the tendency of the brick to bulge upward out of the tray and thereby adapt the case to firmly hold 15 relatively thin slabbed off faces of brick. This invention also includes certain other novel features of construction, which will be more fully pointed out in the following specification and claims.

In the accompanying drawings, I have illustrated the best form of my display case at present known to me. Referring to the drawings, Figure 1 is a plan view of my invention; Fig. 2 is an enlarged section of 20 the same taken on the line 2—2 of Fig. 1, the angle of the gripping surfaces with the vertical being exaggerated for clearness; Fig. 3 is a detail plan view of one of the fastening devices mounted on the bottom of the tray; Fig. 4 is a section through one of 25 the side fastening devices taken on the line 4—4 of Fig. 2 and Fig. 5 is an end view of one of the spacing bars.

As shown in the drawings, I provide a tray 30 having longitudinal side members 6, end members 7 and a bottom 8, said members and bottom being securely joined one to another to form a rigid structure. Extending the length of the case in parallel relation with the members 6 is a series of flexible strips 9, 9^a and 9^b severally adapted to be inserted between rows of brick samples 10. These strips 9, 9^a and 9^b are normally 35 free within the tray, but may be pressed into firm engagement with the samples 10, as 40 fastened by screws 13 at spaced intervals 60 in one of the side members 6 of the tray is a series of metal plates 14 carrying set screws 15. These screws 15 extend through holes in the members 6 and are arranged with their curved ends outward, so as to facilitate 45 manipulating the same. The inner ends of the screws 15 are adapted to impinge against a bar 16 of spring steel, which extends the length of the case and constitutes an abutment for all of the screws 15.

Fastened by screws 13 at spaced intervals 60 in one of the side members 6 of the tray is a series of metal plates 14 carrying set screws 15. These screws 15 extend through holes in the members 6 and are arranged with their curved ends outward, so as to facilitate 45 manipulating the same. The inner ends of the screws 15 are adapted to impinge against a bar 16 of spring steel, which extends the length of the case and constitutes an abutment for all of the screws 15.

To further secure the central strips 9^b against falling out of the case, in the event that the same should be inverted, I secure a series of slotted discs 17 to the bottom 8 and form grooves 18 beneath said discs to receive the heads 19 of screws secured in the lower edges of the strips 9^b. Thus, as will be readily understood, the heads 19 may be inserted in ends of the grooves 18 beyond the discs 17, when the strip 9^b may be moved 70 to carry the shanks of the fastening screws into the slots in the discs 17 and thereby bring the heads 19 into engagement with said discs beneath the margins of the slots. These fastening discs 17, while desirable in 75 the event that the case is to be carried about and subjected to rough handling, are not considered essential to the invention. The peculiar form of the strips 9, 9^a and 9^b insures secure fastening for most uses to 80 which the device is adapted.

An important feature of my invention is the peculiar formation and arrangement of the strip 9, 9^a and 9^b which transmit gripping pressure to the samples. Thus, the side 85 bearing surfaces of each of the strips 9 converge downward so that increased pressure may be applied near the upper corners of the adjacent samples, while the strips 9^b converge upward to produce gripping near 90 100

the lower corners of the central samples in the tray. The strips 9^a are formed with their greatest thickness intermediate the upper and lower edges thereof. By this arrangement the gripping force upon the samples is directed approximately as indicated by arrows in Fig. 2, that is, obliquely downward against the bottom 8 from both sides. In this manner the brick samples are pressed firmly against the bottom of the tray and are prevented from bulging away from the bottom when placed under lateral pressure.

The brick samples 10 are preferably prepared for the case by slabbing-off about an inch of the face of full sized bricks. The screws 15 are withdrawn from engagement with the bar 16 to allow space for the insertion of the samples. Samples illustrating one or a plurality of kinds of brick may now be placed in the case between the several strips 9, 9^a, 9^b and spacing bars 11, so as to present the face of the brick outward. To firmly grip the samples, the several screws 15 are merely turned inward to press the spring bar 16 against the adjacent bar 9, which in turn clamps or grips the samples and others bars 9^a and 9^b. By reason of the resilient nature of the bars 9, 9^a, 9^b and 16, any irregularities or inequalities in the width of the samples, are compensated for, and firm, uniform engagement is obtained.

Obviously the oblique gripping produced by tapering the strips 9, 9^a, and 9^b as shown could also be produced by tapering the edges of the samples 10 and any such substitution of means is considered within the spirit of my invention. I prefer the form shown, however, because the work of preparing a large number of samples for the case is thus minimized.

My improved display case affords inexpensive and convenient means for transporting and displaying brick samples in attractive arrangement.

Having described my invention what I claim as new and desire to protect by Letters Patent is:

1. In a device of the class described, a tray adapted to receive a plurality of brick samples arranged in rows to present the appearance of a wall, a series of flexible spacing strips severally disposed between rows of said samples, means for movably securing said strips to the bottom of said tray and for permitting individual, lateral movement of said strips, a flexible bar extending along one side of the tray in parallel relation to the rows of samples, and set screws threaded in a side of the tray and arranged to impinge at their inner ends against said last mentioned bar to exert lateral gripping pressure upon the rows of samples.

2. In a device of the class described, a tray adapted to receive a plurality of brick samples arranged in rows to present the ap-

pearance of a wall, upwardly projecting sides on said tray, a series of flexible spacing strips severally adapted to be inserted between rows of said samples, a flexible bar extending along the inner face of one side of the tray in parallel relation to the rows of samples, and set screws threaded in said side of the tray and arranged to impinge at their inner ends against said last mentioned bar to exert lateral gripping pressure upon all the rows of samples and upon the spacing strips.

3. In a device of the class described, a tray adapted to receive a plurality of rectangular brick samples arranged in rows, a series of parallel spacing strips severally disposed between rows of said samples, the bearing surfaces between said strips and samples being beveled to direct lateral pressure obliquely downward against the bottom of the tray and means adapted to be manipulated to exert lateral pressure upon the rows of samples.

4. In a device of the class described, a tray adapted to receive a plurality of rectangular brick samples arranged in rows, a series of spacing strips severally disposed between rows of said samples, the bearing surfaces between said samples and strips being beveled to direct lateral pressure obliquely downward against the bottom of said tray, a flexible bar extending along one side of the tray in parallel relation to the rows of samples, and means in engagement with said last mentioned bar adapted to exert lateral pressure upon the rows of samples.

5. In a device of the class described, a tray adapted to receive a plurality of brick samples arranged in rows, a series of strips severally disposed between rows of said samples, one of said strips near a side of the tray having its greatest thickness near its upper edge and another of said strips having its greatest thickness near its lower edge whereby lateral pressure is directed obliquely toward the bottom of the tray, and means adapted to exert lateral gripping pressure upon the rows of samples.

6. In a device of the class described, a tray adapted to receive a plurality of brick samples arranged in rows, strips near the longitudinal sides of said tray having downwardly converging gripping surfaces, a strip near the middle of said tray having upwardly converging gripping surfaces, said strips being severally adapted to be inserted between rows of said samples, and means adapted to exert lateral gripping pressure upon the rows of samples and upon said strips.

7. In a device of the class described, a tray adapted to receive a plurality of brick samples arranged in rows, a series of parallel spacing strips severally disposed between rows of the samples, said strips being free for lateral movement to permit ready

insertion of the samples between them, a flexible bar extending adjacent to the inner face of a side of the tray in parallel relation to the rows of samples and a series of screws threaded in said side of the tray and arranged to extend through said side with their inner ends impinging against

said bar whereby all of the samples and strips may be shifted laterally to exert lateral gripping pressure upon the several 10 samples.

In testimony whereof, I have hereunto signed my name to this specification.

WILLIAM C. KOCH.
